CLAIM

The ornamental design for a lighting device body portion, as shown and described.

DESCRIPTION

FIG. 1 is a front left upper perspective view of a lighting device body portion showing our new design implemented as part of a first lighting device;

FIG. 2 is a rear right lower perspective view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a rear side elevation view thereof;

FIG. 8 is a front side elevation view thereof;

FIG. 9 is a rear right lower perspective view thereof with a clip attached to the first lighting device.

FIG. 10 is a front left upper perspective view of the lighting device body portion implemented as part of a second lighting device;

FIG. 11 is a rear right lower perspective view thereof;

FIG. 12 is a front side elevation view thereof;

FIG. 13 is a right side elevation view thereof;

FIG. 14 is a left side elevation view thereof;

FIG. 15 is a front left upper perspective view of the lighting device body portion implemented as part of a third lighting device;

FIG. 16 is a rear right lower perspective view thereof;

FIG. 17 is a front side elevation view thereof;

FIG. 18 is a left side elevation view thereof; and,

FIG. 19 is a right side elevation view thereof.

The broken lines in the drawings illustrate environmental features and form no part of the claimed design.
